UNITED STATES PATENT OFFICE.

SOLOMON MEYERS, OF SEATTLE, WASHINGTON, ASSIGNOR, BY MESNE ASSIGNMENTS,
TO THE N. J. RICH COMPANY, OF CLEVELAND, OHIO, A CORPORATION OF OHIO.

MUFFLER.

1,144,858.

Specification of Letters Patent. Patented June 29, 1915.

Application filed July 15, 1909. Serial No. 507,868.

To all whom it may concern:

Be it known that I, SOLOMON MEYERS, a subject of the King of Roumania, and a resident of the city of Seattle, in the county of King and State of Washington, have invented certain new and useful Improvements in Mufflers, of which the following is a specification.

My invention aims primarily to provide a muffler which when in position about the neck of the wearer, will fit snugly.

A further object resides in the provision of an improved knitted construction, which will lie smoothly and retain its shape when drawn tightly about the neck, thereby presenting a neat appearance and being comfortable, as contradistinguished from knitted constructions, of which I am aware, wherein upward curling of the rear portion 20 thereof results from the stretching to which they are subjected.

With the above and other objects in view, to be referred to as my description progresses, my invention resides in the features 25 of construction hereinafter described and succinctly defined in my annexed claims.

Referring to the accompanying drawing, in which like numerals of reference indicate like parts throughout: Figure 1 is a view in perspective illustrating my invention in use, and Fig. 2 is a plan view thereof, with a section of the end broken away, and Fig. 3 is an enlarged view somewhat diagrammatically showing the arrangement 35 of the ribs and stitches in the different portions of the neck.

My muffler which is knitted from any suitable material, as will more fully appear hereinafter, comprises a neck part 1, consisting of a rear section 1' and side section 40 1'', to which side sections other sections, as 2, are connected, the same being of such dimensions as to provide ample protection for the chest, as clearly shown in Fig. 1.

45 Rear section 1' has a straight inner edge 1^a which conforms to and normally has even engagement with the back of the neck of the wearer without undue stretching. The edges of side sections 1'' are also straight 50 (see Fig. 2) and parallel and extend from the inner edge 1^a of section 1' at obtuse angles therewith.

In order to prevent the rear section 1' from curling up, and making a better fitting neck portion for the muffler, I elastically 55

knit said section with rows of stitches or ribs *b* parallel with the straight edges of said section and at obtuse angles with the rows of stitches in the section 1'.

Sections 1'' are knitted so that the ribs 60 (*c*) of the knitting run lengthwise thereof and join ribs (*b*), which preferably are thus formed integrally with said diagonally extending ribs (*c*), as will be readily understood. By this formation of sections 1' and 65 1'', stretching thereof incident to bringing the forward end portions of sections 1', and sections 2 into overlapping relation, as illustrated in Fig. 1, tends to pull and hold the outer or free end portion of section 1' 70 down against the back of the wearer.

The fastening means employed by me is of a well known type, the same comprising a headed stud 3 and a socket member 4, secured to respective sections 1'', at suitable 75 points whereby the desired overlapping of said sections at their forward ends, as previously set forth, can be obtained.

My muffler can be knitted by machinery with facility, the various sections forming 80 continuations of one another and as now constructed, ribs (*b*) are knitted full cardigan, racked every round, while ribs (*c*) are racked every half round.

By combining with the diagonal sections 85 1'', a straight intermediate neck section 1', not only is there secured a better fitting neck portion for the muffler, but the elastic racked section 1' stretches sufficiently to conform to the neck, while the racked sections 1'' 90 are less elastic and forming obtuse angles therewith and with the end portions, meet and fit closely together at the wearer's throat. This will be understood from the manner in which these sections are knit, 95 which may be properly proportioned with respect to each other to accommodate and fit different sizes of necks.

Sections 2, are herein illustrated as being 100 knitted scalloped. The detail construction of these sections 2, however, is not material to my invention.

By the particular construction of the neck part 1 of my muffler, aside from overcoming 105 distortion of the muffler during the positioning operation thereof as heretofore set forth, the resulting undesirable features, incident to the wearer putting on his coat, I have provided a muffler which will fit snugly about the neck above the collar. The outer 110

and inner edges of section 1' are substantially parallel. This is also true of the corresponding edges of sections 1'', by which construction sections 1'' will engage over 5 the shoulders without wrinkling.

Having thus fully described my invention, what I claim as new and desire to secure by Letters Patent of the United States is:

1. A muffler of the class described, comprising integrally flat-knit end-portions and an intermediate neck-portion having two diagonally-knit sections racked each half round and a straight central section racked each round, substantially as set forth. 10
2. An integral flat-knit muffler, comprising end-portions in substantial alinement and a connecting shaped neck-portion comprising two offset sections ribbed diagonally but continuously and a straight ribbed central section, and fastening means for holding the end sections in an overlapped position at the front of the wearer's throat, substantially as set forth. 15
3. A flat-knit muffler, comprising two integral ends and a neck-portion, said neck-portion having two diagonally-knit sections forming obtuse angles directly with the respective ends; and being united by a substantially rectangular intermediate section, substantially as set forth. 20
4. A muffler comprising integrally-knitted ends and a connecting neck-portion, consisting of three ribbed sections; two of which extend diagonally from the end-portions and the other section being intermediately positioned in offset relation with the remainder of the muffler, whereby a close-fitting non-curling neck-portion is obtained, substantially as set forth. 25
5. An integral flat-knit muffler, comprising two end-portions in substantial alinement; two connecting diagonal neck-portions, the stitches being racked each half round, and a straight back-portion, the stitches being racked each round, to form an elastic integral rear member, substantially as set forth. 30
6. A muffler comprising a knitted neck part and end sections, said neck part comprising a rear section and side sections, said side and end sections forming continuations of said rear section, said rear section having substantially parallel inner and outer edges and having its rows of stitches extending forwardly at an angle to those of said side sections. 35
7. As a new article of manufacture, a neck- 40

scarf and chest-protector, comprising end-portions integrally knitted with a three-part neck portion approximately of U-shape, having substantially parallel edges, said neck being knitted throughout with ribs extending parallel with said edges, substantially as set forth. 60

8. As a new article of manufacture, a neck-scarf of knitted material comprising end-portions with fastening means therefor, diagonally positioned or offset neck portions at an angle therewith, and a substantially straight rear portion, substantially as set forth. 65

9. As a new article of manufacture, an integrally flat-knit neck-scarf, comprising substantially straight-end portions, and means for fastening the same at the front of the 75 wearer's neck, offset neck portions extending therefrom at an obtuse angle, and an intermediate straight back portion uniting said neck portions, substantially as set forth. 70

10. As a new article of manufacture, an integrally-knit neck-scarf or muffler, comprising substantially straight terminal portions, fastening means therefor, diagonally extending neck portions at an obtuse angle therewith, and an elastic back portion uniting the latter; to form an integral self-conforming muffler, substantially as set forth. 80

11. As a new article of manufacture, an integral or continuous flat-knit muffler, comprising two end portions, associated fastening means, racked neck portions respectively attached to the ends and extending diagonally at an obtuse angle, and a connecting back portion suitably racked to form an elastic self-conforming rear section for the 90 muffler, substantially as set forth. 95

12. A continuously knit neck-scarf comprising semi-elastic portions and an integral elastically knit portion centrally disposed therebetween, substantially as set forth. 100

13. An integral flat-knit muffler, comprising two end-portions in substantial alinement; two connecting neck-portions at an obtuse angle therewith and a straight central back-portion with edges substantially parallel with those of the end-portions, substantially as set forth. 105

Signed at Seattle, Washington, this 27 day of February, 1909.

SOLOMON MEYERS.
